UNITED STATES PATENT OFFICE.

WILLIAM C. LOHSE, OF STRATFORD, CONNECTICUT, ASSIGNOR TO THE R. NEUMANN HARDWARE CO., A CORPORATION OF NEW JERSEY.

DESIGN FOR TOP BAND FOR BAG FRAMES.

Application filed December 8, 1925. Serial No. 15,687. Term of patent 7 years.

To all whom it may concern:

Be it known that I, WILLIAM C. LOHSE, a citizen of the United States, residing at Stratford, in the county of Fairfield and State of Connecticut, have invented a new, original, and ornamental Design for a Top Band for Bag Frames, of which the following is a specification, reference being had to the accompanying drawing, forming a part thereof.

In said drawing, Figure 1 is a plan view of a top band showing my new design; Figure 2 is a side elevation of the same; and Figure 3 is a view of one of the ends of the top band.

I claim:

The ornamental design for a top band for bag frames, as shown.

WM. C. LOHSE.
